UNITED STATES PATENT OFFICE

MAX A. MILLER, OF NEW YORK, N. Y., ASSIGNOR TO MILWELL ELECTRIC DEVICES CORPORATION, OF NEW YORK, N. Y.

METHOD OF AND APPARATUS FOR TESTING METALS AND ALLOYS

Application filed January 5, 1929. Serial No. 330,564.

This invention relates to methods of and apparatus for testing metals, based upon their magnetic characteristics or the lack of it, and more particularly the invention refers 5 to a method for testing nickel coins whereby spurious and counterfeit coins can be easily detected and isolated from the others.

Slot machines and automatic vending machines generally, which are rendered operative by the insertion of a nickel or similar coin are not proof as a rule against the insertion of slugs of a size and weight approximately corresponding to those of a genuine coin.

As a result, the owners of vending machines 15 and slot operated devices are frequently victimized in this respect by unscrupulous users and their earnings are thereby reduced a material extent.

It is therefore desirable to provide devices 20 and machines of the character specified, with means for the automatic selection of the coins inserted, said means being of a nature to prevent the operation of the machine or device when a spurious coin or a counterfeit or forged coin is inserted.

According to the present invention an automatic selection of the coins may be had by basing the operation of the selective devices employed upon the magnetic characteristics 30 of the metal out of which a genuine coin is made. For instance, I have found that a United States nickel is less susceptible to magnetic attraction than a Canadian nickel because the percentage of nickel in the alloy 35 used for the production of United States nickels is smaller.

For the same reason, spurious coins containing a material amount of iron are also more responsive to magnetic action than a 40 genuine United States nickel while other coins totally made of brass or pewter or other non-metallic metal or alloy, respond to magnetic action in a still different way.

I have therefore developed a simple and 45 reliable method of detecting spurious and counterfeit nickels which lends itself to be applied in practical form to the operation of vending and slot machines generally. However, since this method of detection is 50 based as stated, upon certain physical charac-

teristics of the metals or alloys out of which various coins and slugs may be made, it may be stated broadly that the invention relates in reality to a method for testing metals based on a new principle, that is, the utilization of 55 the magnetic characteristics of each metal as compared with a standard to be predetermined in advance.

The primary object of this invention is to provide a simple and novel method of detecting and separating spurious and counterfeit coins, as well as foreign nickels from genuine 60 United States nickel coins.

Another object of the invention is to provide an apparatus embodying the method mentioned, said apparatus being simple and reliable enough to warrant its practical application in slot and vending machines of any 65 well known type.

A further object of the invention is, broadly, to provide a method for testing metals and alloys according to their magnetic properties, as compared to those possessed by a standard of predetermined and known composition. 70

Other objects and advantages of the present invention will more fully appear as the description proceeds and will be set forth and claimed in the appended claims.

As stated in the premises, my invention is 80 based upon the fact that metals or alloys containing a greater or lesser amount of magnetic material are attracted by a given magnet with a greater or lesser intensity. In the 85 course of my experiments I have found that not only non-magnetic metals and alloys were not attracted by a magnet but that they were actually repulsed to a more or less degree. This led me to further experimenting, and as a result I have perfected a method of isolating 90 spurious and foreign nickels from genuine United States nickel coins to a point where it is susceptible of many practical applications.

My invention is illustrated in the accompanying drawings in a more or less systematic form, said drawings being intended by way of example and not in a limiting sense, to assist in understanding the fundamental features of my invention. 95

Referring to said drawings:—

Fig. 1 is a diagrammatic plan view of a device embodying a method of magnetic detection which may be used for separating 5 counterfeit and foreign nickel coins from United States coins;

Fig. 2 is another plan view of the same showing the operation of the device when a United States nickel coin is used;

Fig. 3 is a diagrammatic front elevation 10 of a device in which not only the attraction or the lack of it exerted by a magnet upon a metal or alloy is used, but also the repulsion exerted upon nonmagnetic metals or alloys;

Fig. 4 is a plan view thereof, partly sectioned to show the arrangement of the coin 15 passages;

Fig. 5 is a side sectional view of the same 20 through line 5—5 of Fig. 4;

Fig. 6 is a side sectional view of the same through line 6—6 of Fig. 4;

Fig. 7 is a detail front elevation of the 25 magnet employed for the rejection of non-metallic coins; and

Fig. 8 is a fragmentary side elevation 30 partly sectioned of a device similar to that illustrated in Figs. 3 to 7 illustrating the possibility of adjusting the magnetic action by varying the distance between the magnet and a coin.

The device illustrated in Figs. 1 and 2, 35 is based upon the fact that if a mass of pure nickel or a suitable alloy containing a magnetic metal is placed opposite the poles of a horse-shoe magnet and is spaced therefrom a certain distance if a disk of metal or alloy is interposed between the magnet and the magnetic metal, the latter will be attracted 40 only if the metal or alloy thus inserted contains a certain amount of magnetic material while if no magnetic material is present the metal disk will act as an effective shield preventing any magnetic action from taking 45 place.

In other words, the device is based upon the 50 magnetic permeability of the metal which is being tested. Referring to Figs. 1 and 2, 10 designates a horse-shoe magnet formed with two poles 11, 12 the end faces of which 11', 55 12' are in line with the inner wall 13 of a coin passage 14.

A piece of metal bar 15 made of nickel or 60 some alloy containing magnetic material, having a cross section about equivalent to that of an ordinary nickel coin is placed end-wise opposite poles 11, 12 of the magnet, and is spaced therefrom a distance somewhat greater than the thickness of an ordinary 65 nickel coin.

Said metal bar is provided with an arm 16 70 pivotally mounted at 17, permitting the magnet to attract said bar against the action of a sensitive retaining spring 18. Said bar is normally retained by said spring against a

stop 19, and its angular displacements towards the magnet is preferably limited by another stop 20, allowing for a clearance to remain between the bar and the poles of the magnet sufficient for the passage of a nickel 70 coin.

Arm 16 has a rear extension 21 shown in dotted lines which is formed with an upwardly projecting lug 22 normally blocking passage 14' beyond the magnet; however, a slight angular displacement of arm 16 and bar 15 towards the magnet is sufficient to move lug 22 to one side of the passage as shown in Fig. 2.

When a spurious coin made of brass or 80 aluminum or zinc alloy, etc., is run through passage 14 up to and between the magnet and the bar, the bar being in the meantime held in its outer position shown in Fig. 1 by the spring, no action whatever will take place 85 upon the bar and therefore the progress of the coin will be stopped by lug 22. If a genuine United States coin is inserted instead, a slight attraction will take place, sufficient to move lug 22 to one side as shown in Fig. 2. 90

However, the attraction is solely exerted upon bar 15 due to the magnetic permeability of the coin, but the coin itself contains so little nickel that the magnet will not attract it 95 sufficiently to stop its progress; therefore, the coin can continue on its way past lug 23 as shown in Fig. 2.

On the other hand, if a metal disk or a coin 100 containing a larger percentage of nickel such as for instance, a Canadian nickel is inserted, the same will be attracted by the magnet and held. If the metal disk or slug is made of iron, the magnetic action will be so strong 105 that a material force must be exerted in order to remove it.

It is obvious therefore, that a United States nickel will freely pass beyond the magnet and advance towards the mechanism controlling the vending or coin operated device as shown at 23 in Fig. 2; a spurious coin made of non-magnetic material will remain loose between the magnet and the metal bar; a Canadian nickel or other coin containing a similar amount of nickel will lightly stick to the poles 115 of the magnet and if an iron counterfeit is inserted it will stick to the magnet fast enough to require some sort of mechanical action to detach it therefrom.

It is obvious that iron counterfeit coins 120 could also be stopped by a separate magnet before they reach the position between magnet 10 and bar 15. The magnet can be a permanent magnet or an electromagnet and must be placed in the proper position with respect to metal bar 15 if it is to discriminate properly between genuine coins and counterfeit coins. This position depends upon the size, shape and magnetic properties 125 of the bar 15 and the magnet 10 and can easily be determined by actual test. 130

As previously stated, I have found that when a counterfeit coin made of aluminum, brass or other alloys not containing nickel or any other magnetic metal is placed before a magnet the same will be repulsed by the magnet and caused to tilt away therefrom.

By taking advantage of this action which I believe I am the first to have discovered, I have devised a simpler and more effective 10 method of detection of counterfeit coins which is embodied in the device shown in Figs. 3 to 7. In the same 30 designates a coin chute at the outer end of which a coin such as 32 can be inserted. Said chute is 15 mounted on a stand 33 and is slightly inclined downwardly in its intermediary portion 34 ending with a downwardly directed tract 35, provided with a discharge outlet 36.

Two magnets 37, 38 which may either be 20 permanent, or electromagnets as shown, are placed in succession at one side of the intermediary tract 34 of the chute. The core 39 of the first magnet is spaced from the inner wall 41 sufficient to accommodate a coin between said core and said wall 40, while the 25 end of the core 42 of the second magnet is flush with the inner surface of wall 40.

An opening such as 43 is provided through wall 40 opposite magnet 37, said opening being 30 large enough to permit the passage of a nickel coin in a transversal sense, and reaching to the bottom of the chute as shown in Figs. 3, 5.

Another opening 44 is provided through 35 the other wall 45 of the chute directly opposite magnet 38, and a discharge tube 46 displaced in correspondence of said opening, said tube extending away from the magnet and downwardly as at 47 and being provided 40 with a discharge outlet 48.

Another chute 49 is provided underneath space 41 for the discharge of the coins which may reach said space by the action of magnet 37; furthermore, a rectangular tubular member 50 is provided above space 41, said member 45 extending in an upward direction and acting as a guide for a piston 51 which is shown in its upward position and which may be caused to reciprocate so as to force a coin 50 from space 41 into chute 49. The means for operating this piston are not shown but it will be understood that any suitable well known mechanism may be employed to this end.

55 The operation of the device is as follows:—If a genuine United States nickel coin is inserted through opening 31, the same will run by and beyond opening 43 and will also continue in the same direction and pass beyond core 42 of magnet 38 ultimately reaching front 35 of the discharge outlet 36.

If a coin made of copper, aluminum, zinc, brass or pewter or some other alloy free of any magnetic metal, is inserted through the 60 chute it will pass by and beyond opening 43,

but as it reaches the space in front of core 42, it will be more or less violently repulsed directly into discharge tube 46.

If on the other hand, a counterfeit coin containing a large amount of iron, or else a 70 foreign coin containing a larger percentage of nickel than the United States nickel coin, is used, when the same on its way towards the discharge end of chute 30 reaches a position opposite core 39 of magnet 37, the action of said magnet will be powerful enough to attract said coin and force it sidewise through opening 43, causing the coin to stick to the end of core 39. The attracted coin itself may be used as will be understood to 75 close a circuit or to otherwise start the operation of the mechanism employed to operate piston 51 so that upon a coin being so attracted by core 39, the piston will move 80 downwardly and force the coin beyond said core and within chute 49 from whence it will be discharged into a suitable receiver. 85

By way of example, Figs. 3, 4 and 5 show two terminals 52, 53 of an electric circuit represented by two wires 54, 55 which are 90 short circuited by a coin when it is attracted by core 39. The electric circuit which becomes thus energized may cause the operation of piston 51 in any suitable manner as 95 will be understood.

I have found in practice that the repelling action of magnet 38 is intensified if a shading coil 56 is placed in front of the magnet so as to shield its upper half as shown in Fig. 7. 100

I have also found that the action of the repelling magnet is particularly effective, reliable and efficient when the distance between the bottom of passage 34 and the center of core 42 is greater than the radius of the coin 57 as Fig. 6 clearly shows, this being 105 presumably due to the fact that the greater the distance between the core and the lower edge of the coin, the greater the leverage.

While in the course of this description, I 110 have mentioned discharge outlets 36, 48 and opening 31, it will be understood that these various openings may lead to any other passage such as may be required for the operation of the machine onto which the device 115 is applied.

As stated in the premises, the inventive idea may also be applied for the testing of metals and alloys generally, for instance, for the purpose of determining the amount of 120 a given magnetic metal therein contained. For this purpose, it may be desirable to vary the distance between a passage or conduit through which a metal disk may run, and the core of the magnet, in order to provide a 125 basis for comparison between various metals and alloys tested.

As an example of an apparatus which may be built along these lines, I illustrate in Fig. 8 a device where a magnet 58 is mounted so 130

as to be movable to and from passage 59 by means of an adjusting screw 60 as will be understood.

By means of a device of this type, it is therefore possible to determine by comparison the relative magnetic attraction or repulsion exerted by the magnet upon disks made of different metals or alloys and similarly it is also possible to determine the magnetic properties of such metals and alloys in relation to a given standard.

It will be observed that the intensity of the magnetic action is not only a function of the magnetic flux generated by the magnet, but is also a function of the distance between the core of the magnet and the piece of metal or alloy tested.

It is therefore obvious that although I have described a preferred arrangement where the second magnet practically exerts no attraction whatever upon United States nickels, it is quite possible to conceive of an arrangement where said magnet may generate a magnetic flux strong enough to attract these coins, preventing their being discharged through the end discharge passage, the pieces being subsequently detached by some mechanical means such as described in connection with the first magnet. It is also conceivable that such pieces may pass beyond the first magnet by so regulating the magnetic flux generated thereby and the distance from the passage that only pieces containing a higher amount of magnetic metal will be attracted.

The invention accordingly embraces in a generic sense the use of a magnet or magnets for the separation of metals or alloys containing different amount of magnetic material and for the further separation of metals or alloys containing no magnetic metal whatever.

No attempt has been made towards illustrating in detail various ways in which the invention can be applied. It is obvious that devices of various designs can be produced embodying the inventive idea in ways different from those shown and described; however, since the method itself is believed to be broadly new, all such devices and arrangements are held to fall within the scope of the present invention.

I accordingly reserve myself the right to carry my invention into practice in all those ways and manners which may enter, fairly, into the scope of the appended claims.

I claim:

1. In a device of the class described, the combination with a longitudinal passage through which metal disks may be made to travel, of a magnet transversely arranged at one side thereof, said magnet being regulated to exert practically no action upon disks containing a predetermined amount of magnetic metal, and to repel disks made of diamagnetic metal, an opening through one of the

sides of said passage located at a point nearer to the point of insertion of said disks, another magnet placed in cooperative relation to said opening, adapted to attract through said opening disks containing a relatively high amount of magnetic material, and means for detaching from said magnet, the disks thus attracted.

2. In a device of the class described, the combination with a longitudinal passage through which metal disks may be made to travel, of a magnet transversely arranged at one side thereof, said magnet being regulated to exert practically no action upon disks containing a predetermined amount of magnetic metal, and to repel disks made of diamagnetic metal, an opening through one of the sides of said passage located at a point nearer to the point of insertion of said disks, another magnet placed in cooperative relation to said opening, adapted to attract through said opening disks containing a relatively high amount of magnetic material, and means for shifting disks thus attracted transversely of said magnet in order to detach them therefrom.

3. In a device of the class described, the combination with a longitudinal passage through which metal disks may be made to travel, of a magnet transversely arranged at one side thereof, said magnet being regulated to exert practically no action upon disks containing a predetermined amount of magnetic metal, and to repel disks made of diamagnetic metal, an opening through one of the sides of said passage located at a point nearer to the point of insertion of said disks, another magnet placed in cooperative relation to said opening, and spaced therefrom, adapted to attract through said opening disks containing a relatively high amount of magnetic material, a discharge passage in correspondence of the space between said second mentioned magnet and said opening, and means for forcing disks attracted by said magnet into said discharge passage.

4. In a device of the class described, the combination with a longitudinal passage through which metal disks may be made to travel, of a magnet transversely arranged at one side thereof, said magnet being regulated to exert practically no action upon disks containing a predetermined amount of magnetic metal, and to repel disks made of diamagnetic metal, a discharge passage beyond said magnet, an additional transversal discharge passage opposite said magnet, an opening through one of the sides of said passage located at a point nearer to the point of insertion of said disks, another magnet placed in cooperative relation to said opening, adapted to attract through said opening disks containing a relatively high amount of magnetic

material, and means for detaching from said magnet, the disks thus attracted.

5. In a device of the class described, the combination with a longitudinal passage 5 through which metal disks may be made to travel, of a magnet transversely arranged at one side thereof, said magnet being regulated to exert practically no action upon disks containing a predetermined amount of magnetic 10 metal, and to repel disks made of diamagnetic metal, a discharge passage beyond said magnet, an outwardly directed transversal discharge passage opposite said magnet, an opening through one of the sides of said passage located at a point in advance of said magnet, another magnet placed in cooperative relation to said opening, and spaced therefrom, adapted to attract through said opening disks containing a relatively high amount of magnetic 15 material, a discharge passage in correspondence of the space between said second mentioned magnet and said opening, and means for forcing disks attracted by said magnet into said discharge passage.
- 20 6. In a device of the class described, the combination with a longitudinal passage through which metal disks may be made to travel, of a magnet transversely arranged at one side thereof, said magnet being regulated to exert practically no action upon disks containing a predetermined amount of magnetic metal, and to repel disks made of diamagnetic metal, an opening through one of the sides of said passage located at a point nearer to the 25 point of insertion of said disks, another magnet placed in cooperative relation to said opening, adapted to attract through said opening disks containing a relatively high amount of magnetic material, and means for 30 detaching from said magnet, the disks thus attracted, said means being controlled by said disks.

7. In a device of the class described, the combination with a longitudinal passage 45 through which metal disks may be made to travel, of a magnet transversely arranged at one side thereof, said magnet being regulated to exert practically no action upon disks containing a predetermined amount of magnetic 50 metal, and to repel disks made of diamagnetic metal, an opening through one of the sides of said passage located at a point nearer to the point of insertion of said disks, another magnet placed in cooperative relation to said 55 opening, adapted to attract through said opening disks containing a relatively high amount of magnetic material, means for detaching from said magnet, the disks thus attracted, and an electric circuit controlling 60 said means, adapted to become energized by the action of said disks.

8. In a device of the class described, the combination with a longitudinal passage through which metal disks may be made to 65 travel, an opening through one of the sides

of said passage, and a magnet placed opposite said opening adapted to attract through said opening disks containing a relatively high amount of magnetic material, of an ejecting member adapted to detach from said magnet 70 the disks thus attracted, and an electric circuit controlling said ejecting member, the status of said circuit being altered by said disks when thus attracted.

9. In a device of the class described, the 75 combination with a longitudinal passage through which metal disks may be made to travel, an opening through one of the sides of said passage, and a magnet placed opposite said opening adapted to attract through 80 said opening disks containing a relatively high amount of magnetic material, of an ejecting member adapted to detach from said magnet the disks thus attracted, and a normally open electric circuit controlling said 85 ejecting member, said circuit being completed through one of said disks when thus attracted and becoming then operative to actuate said ejecting member.

10. In a device of the class described, the 90 combination with a longitudinal passage through which metal disks may be made to travel, of an electromagnet transversely arranged at one side thereof, said electromagnet being regulated to exert practically no 95 action upon disks containing a predetermined amount of magnetic metal, and to repel disks made of diamagnetic metal, a discharge passage beyond said magnet, an outwardly directed transversal discharge passage opposite said magnet, and a shading coil placed in front of said magnet so as to shield its upper half portion.

11. In a device of the class described, the 100 combination with a longitudinal passage 105 through which metal disks may be made to travel, of an electromagnet transversely arranged at one side thereof, said electromagnet being regulated to exert practically no 110 action upon disks containing a predetermined amount of magnetic metal, and to repel disks made of diamagnetic metal, a discharge passage beyond said magnet, an outwardly directed transversal discharge passage opposite said magnet, and a shading coil placed in 115 front of said magnet so as to shield its upper half portion, the distance between the bottom of said longitudinal passage and the axis of said magnet being greater than the radius of said disks.

MAX A. MILLER.
